UNITED STATES PATENT OFFICE.

AXEL A. STROM, OF AUSTIN, ILLINOIS.

RAILWAY-FROG.

SPECIFICATION forming part of Letters Patent No. 395,929, dated January 8, 1889.

Application filed August 21, 1888. Serial No. 283,316. (No model.)

To all whom it may concern:

Be it known that I, AXEL A. STROM, a citizen of the United States, residing at Austin, in the county of Cook and State of Illinois, 5 have invented a new and useful Improvement in Railway-Frogs, of which the following is a specification.

The object of my improvement is principally to supply a construction of frog which 10 shall meet the requirements becoming more and more urgent on the part of users that the device shall possess as properties extreme lightness, comparatively speaking, necessary strength in the security of its connected parts, 15 as also, of course, in the metal of which it is formed, accessibility of its parts for permitting readily the removal of dirt, snow, ice, &c., and economy of material. To attain strength in the device as a whole, frogs have hitherto, 20 as a common manner of their construction, been rendered massive, and consequently heavy and correspondingly expensive, by providing so-called "filling" in the spaces between the rails forming them. The filling 25 also, as a further disadvantage, tends, owing to the height to which it is thought necessary to have it extend between the rails, to cause fracturing of the flanges of the wheels of the rolling-stock as they become worn on their 30 treads with use, causing the flanges eventually to meet the filling-blocks.

By my improved construction I am enabled to dispense with the filling without thereby depriving the frog of the necessary bracing, 35 which filling affords between the rails and of convenient accessibility between the rails for removing accumulations of dirt, snow, ice, &c.

A further object of my improvement is to 40 so construct the point of the frog that the shorter of the two beveled point-rails shall not, as hitherto, be liable to the effect of pounding by the wheels of the rolling-stock, which tends to sever the connection with its com- 45 panion rail.

My invention consists in details of construction and combinations of parts.

In the drawings, Figure 1 is a plan view of a railway-frog of my improved construction. 50 Fig. 2 is a horizontal section of the same, taken below the heads of the rails. Fig. 3 is

a cross-section. Fig. 4 is a plan view of the blank before it is bent to form the brace shown in Figs. 1 and 2 between the frog-rails. Fig. 5 is a horizontal section of the 55 frog, taken below the heads of the rails, and showing a modified construction of the bracing medium.

A are the wing-rails, of ordinary form, and B and B' are respectively the shorter 60 and longer point-rails. Where the rail B is secured at its beveled surface to the point-rail B' the laterally-reduced head portion is beveled off on its top toward the extremity, as shown at r in Fig. 1, so that the wheels of the 65 rolling-stock in moving onto the frog-point will not impinge against the extremity of the rail B and by pounding against it gradually sever its connection with the rail B'.

C is a brace or truss, the form shown at opposite sides of the frog-point in Fig. 2 being produced from a blank, C', of the shape represented in Fig. 4, comprising a metal bar, preferably of rectangular form and bent edge-wise toward its opposite ends to produce 75 upon the central or body portion, o, the outwardly-oblique extensions p and the horizontal outwardly-extending extremities n. The brace is formed from the blank by bending the latter at about the centers of the extensions p to bring the body portion o on a plane lateral to that upon which the extremities n extend, and thereby forming the extensions p into troughs. The width of the brace is such as to cause it to fit in the space which receives it between rails, so that when adjusted in position the extremities n, thus forming foot portions, are against the web of one (say a wing) rail, while the body portion o is against the opposing side of the web of 85 the adjacent point-rail, the troughs p resting against the flange of the wing-rail, and the parts o and n of the brace being, by preference, beveled on corresponding sides toward the lateral edges, to cause them to conform to 90 the angular shape of the spaces at the sides of the rails between the heads and flanges. Where the foot portions n are in contact with the web, they are secured to the latter, each 95 preferably by two bolts, m, while the part o of the brace may be secured to the web of the adjacent rail by the rivets m', which secure

the rails B and B' together toward their points, additional rivets being used, if required, as in Fig. 1, where the body portions of the braces are slightly bent to bring them 5 against the opposite sides of the web of the pointed portion of the rail B' where it extends beyond the rail B. If desired, the foot portion n at the end of a brace C, which is secured near the flaring extremity of a wing- 10 rail, may be bent horizontally, as shown in Figs. 1 and 2, to extend across the space between rails and afford a foot-guard, l.

A frog formed, as described, with braces of the construction set forth, besides being light 15 and strong, presents no material obstruction to access between the rails for the removal by sweeping or the like of dirt, snow, ice, &c.

A single brace C may be employed for one side of a frog at the point, as in the case of 20 spring rail-frogs.

The brace C may be modified in its construction, as shown in Fig. 5. The latter comprises, practically, a section of the brace already described, and which has one of the 25 foot portions n, the other foot portion being afforded by the severed section of the body portion. Thus, if desired, each of the braces C first described may be severed between the troughs p near its opposite ends into two 30 sections, each forming a shorter brace of the form shown in Fig. 5, and which must of course be secured in position with its foot portions respectively against the opposing web-faces of adjacent rails.

35 While I have shown and described my improved brace in its application to a railway-frog, I do not wish to confine myself to its use in that particular connection, since it is useful for connecting rails in other situations.

40 It will be noticed that my improvement af-

fords flanged bearings for bracing the frog-point at opposite sides and against the flanges of the wing-rails, thereby bracing the point not only against lateral but also against vertical movement, the troughs p, which are practically flanges of the brace, resting upon the flanges of the wing-rails. 45

What I claim as new, and desire to secure by Letters Patent, is—

1. In a railroad-frog or the like, the combination, with adjacent rails, of a brace, C, formed of a bent metal bar having foot portions n at opposite ends and an intermediate trough, p, substantially as and for the purpose set forth. 50

2. In a railway-frog, the frog-point comprising a point-rail, B', and a point-rail, B, secured to the rail B' and having its wedge-shaped end beveled on its upper side, as shown at r, in a downward direction toward 60 the pivoted end of the frog, substantially as described.

3. In a railway-frog or the like, the combination, with adjacent rails, of a brace, C, comprising a body portion, o, having foot portions n at opposite ends extending laterally of the body portion, and a trough, p, between each foot portion and the adjacent end of the body portion, substantially as and for the purpose set forth. 65

4. A rail-frog having its point braced on opposite sides by means of flanged bearings resting flatwise against the adjacent flanges of the wing-rails and secured flatwise to the web portion of the point, substantially as described. 70

AXEL A. STROM.

In presence of—

CHAS. JOHNSON,
J. W. DYRENFORTH.
